INVENTOR
F. H. Wilbur

Howard, Denison
BY
ATTORNEY.

UNITED STATES PATENT OFFICE.

FREDERICK H. WILBUR, OF BINGHAMTON, NEW YORK

DOOR-LIFTING DEVICE.

Application filed March 30, 1923. Serial No. 628,803

To all whom it may concern:

Be it known that I, FREDERICK H. WILBUR, a citizen of the United States of America, of Binghamton, in the county of Broome, in the State of New York, have invented new and useful Improvements in Door-Lifting Devices, of which the following, taken in connection with the accompanying drawings, is a full, clear, and exact description.

This invention relates to a door lifting device adapted to be used more particularly in connection with swinging doors for garages and analogous buildings where the doors are usually wide and heavy and are more or less liable to sag to such an extent as to interfere with their free operation unless some provision is made for supporting and lifting them when opened.

The main object of this invention is to provide simple and efficient means for supporting and lifting the door clear of the garage floor or approach thereto, as the door is opened and closed, and particularly when opened so as to avoid friction with the floor if the door opens inwardly and to avoid friction with the approach of snow and ice thereon if the door opens outwardly.

In other words, I have sought to hinge the door to the frame in such manner that it may be moved vertically relatively to the frame by suitable operating means provided therefor, which also permits the door to drop against or in close proximity to the sill when closed.

Other objects and uses relating to specific parts of the device will be brought out in the following description.

In the drawings:

Figure 1 is a face view of an outwardly swinging door and adjacent portion of the frame, partly in section, showing a modified form of my invention in which the door may be raised when closed preparatory to opening the same.

Figure 2 is a vertical sectional view, partly broken away, taken on line 4—4, Figure 1.

Figure 3 is an enlarged sectional view taken on line 5—5, Figure 1.

Figure 4 is an enlarged detail sectional view, partly broken away taken on line 6—6, Figure 1.

In Figures 1 to 4 inclusive, is shown a

door frame —22— of a garage or other building —21— for receiving a door —23— which is hinged along one of its upright edges to the adjacent side of the frame by hinge sections —24— and —25— and a pivotal pin or bolt —26— extending through registering openings in the sections —24— and —25—.

The lower end of the hinge bolt or pin —26— is seated in the sill as —27— and has its upper end extended some distance above the uppermost hinge section —25— to permit the door to be raised a limited distance clear of the sill or floor without disengaging the hinge sections from the bolt.

This door is adapted to swing outwardly from its closed position against the lintel as —28— and is provided with lock pins —29— and —30— projecting respectively below its lower edge and above its upper edge near the free upright edge opposite that which is hinged to the door frame.

The lower locking member is adapted to enter a socket —31— in the sill of floor —27— while the upper locking member —30— is adapted to enter a similar socket —32— in the upper side of the lintel —28— for holding the door in its closed position against accidental opening.

A bracket —33— is hinged at one end to the upright bolt —26— to swing horizontally and is preferably bifurcated to normally rest upon supporting sections —34— which are hinged to the adjacent upright member of the door frame and embrace the rod or bolt —26— as shown in Figure 3.

The opposite or inner end of the bracket —33— extends from the bolt —26— substantially half way across the face of the door and is held in close proximity to said door by a guide plate —35— which is secured to the door to form therewith, a lengthwise slot of sufficient vertical height to permit the door to be raised and lowered relatively to the bracket.

A hand lever —36— is pivoted intermediate its ends at —37— to the door and has its end opposite the handle connected by a link —38— to the inner end of the bracket —33—, the arm of the lever between the link —38— and fulcrum —37— being considerably shorter than the handle portion of the lever to enable the door to be raised easily by the operator.

That is, assuming that the door is closed and its locking members —29— and —30— are seated in their respective sockets —31— and —32— then by raising the handle end 5 of the lever —36— upwardly will cause a corresponding upward movement of the door relatively to the frame and bracket sufficient to withdraw the locking members —29— and —30— from their respective 10 sockets —31— and —32— whereupon the elevated door with the lever thereon may be swung upon its hinge connections to an open position with its lower edge a considerable distance above the approach or sill.

15 The link —38— normally stands in a substantially vertical position while the lever —36— is adapted to rock not only between the position shown by dotted lines in Figure 3, but beyond to approximately the vertical plane of the link —38— thereby bringing the pivot or fulcrum —37— nearly or 20 directly over the pivotal connection as —39— between said lever and link.

I claim:

- 25 1. The combination with a door frame and a door hinged along one of its upright edges to the frame, the hinge connection including an upright pivotal bolt, a bracket lying in close proximity to one face of the door 30 and having one end hinged to the pivotal bolt and its other end extended to a point substantially midway between the opposite upright edges of the door, a guide plate secured to the door and impressing the inner 35 end of the bracket to hold the same against lateral swinging movement relatively to the door, said guide being of sufficient vertical height to permit the door with the guide thereon to be raised and lowered relatively 40 to the bracket, means for supporting the outer end of the bracket against downward movement, and means operatively connected to the inner end of the bracket and to the door and operable at will for raising and

lowering the door relatively to said bracket. 45 2. The combination with a door frame and a door, a pivotal bolt extending vertically along one of the upright edges of the door, hinge sections connected respectively to the door and to the frame, the hinge sections on the door being journaled on the pivotal bolt, a bracket hinged to the pivotal bolt and extended partially across the door in proximity thereto, a hand lever pivoted to the door between the upright edges thereof, and a link connecting said lever with the bracket whereby movement of the lever about its fulcrums on the door will be transmitted to said door for raising and lowering the same. 60

3. The combination with a door frame and a door hinged to the frame to swing about a vertical axis, a bracket hinged to the frame to swing about a vertical axis and extended part way across the door, a link connected to the bracket, and a hand lever pivoted to the door and operatively connected to the link to swing about a horizontal axis for raising and lowering the door. 65

4. The combination with a door frame and a door hinged to the frame to swing about a vertical axis, a bracket hinged to the frame to swing about a vertical axis and extended part way across the door, a link connected to the bracket, and a hand lever pivoted to the door and operatively connected to the link to swing about a horizontal axis for 70 raising and lowering the door, and a guide on the door embracing a portion of the bracket for holding the door and bracket 75 against relative swinging movement.

In witness whereof I have hereunto set my hand this 14 day of March, 1923.

FREDERICK H. WILBUR.
